UNITED STATES PATENT OFFICE.

CHARLES PARIDY, OF BELLEVILLE, ILLINOIS.

LOCK BOLT.

Application filed April 20, 1925. Serial No. 24,415.

To all whom it may concern:

Be it known that I, CHARLES PARIDY, a citizen of the United States, residing at Belleville, in the county of St. Clair, in the 5 State of Illinois, have invented certain new and useful Improvements in Lock Bolts, of which the following is a specification containing a full, clear, and exact description, reference being had to the accompanying 10 drawing, forming a part hereof.

My invention consists in the novel construction and combination of parts herein-after particularly described and distinctly claimed.

15 The object of my invention is to provide an improved "lock-bolt", which may be used in the many places where ordinary nuts and bolts are now used, but the primary object of my invention is to provide an improved lock-bolt for use in connection with the building or constructing of railroads in making "joints" and which will, if adopted, eliminate the now common use of the nuts on the bolts when making "joints", or when 20 joining two railway rails together, and which invention will be simple in construction, and of low cost to manufacture.

In the drawing:

Fig. 1 is a sectional end-elevation of a 30 railroad-rail having my invention applied thereto, the section being taken on the line 1-1 of Fig. 2, and

Fig. 2 is a side-view of a pair of railroad-rails joined together, showing how my invention is used in this class of work.

Referring now to the drawing by numerals, the numeral 1 designates the ball of a railroad-rail, while 2 designates the web thereof and 3 the base thereof.

40 The numeral 4 designates the usual fish-plate as used in the present day construction of railroads, while the numeral 5 designates a fish-plate having studs 6 riveted or otherwise secured thereto.

45 Said studs 6 are provided with collars 7 upon which are pivotally mounted a plurality of inverted Y-shaped pawls 8.

Said fish-plates 5 are also provided with a plurality of screw-threaded holes and the 50 threads of the latter are adapted to re-

ceive the screw-threads formed upon the outer periphery of a plurality of bolts 9.

Said bolts 9 are provided with a plurality of longitudinal V-shaped slots or grooves 10; the latter being cut to extend the full 55 length of the said screw-threads.

The numeral 11 designates the arms of the said pawls 8.

My invention is used in the following 60 manner:—

When it is desired to join two railway-rails together, as in the construction of a railroad, and my invention is being used in said construction, the rails are placed end to end as in the position shown in Fig. 2 65 of the drawing, and, as the fish-plates 4 and 5 are placed into position, the bolts 9 are inserted and screwed into holes provided therefor, and a wrench is then applied to the heads of said bolts and they are 70 tightened as tight as possible.

The fish-plate 5 already occupying the position shown in Fig. 2, brings the plurality of pawls 8 in position ready for the workman to move one of the arms 11 of 75 said pawls 8 in position to engage one of the plurality of slots or grooves 10 in said bolts 9.

It is apparent that no matter how much jar or shaking the said bolts or pawls are 80 subject to, the pawls will prevent the said bolts 9 from unscrewing, thereby preventing the rails from becoming unjoined.

While I have illustrated certain details which I deemed to be particularly effective, 85 and have illustrated a construction which is very cheap to make and easy to be assembled, I do not wish to be limited to these details, as it is obvious that many changes may be made therein without departing 90 from the spirit or scope of my invention.

Having thus described my invention, what I claim as new and desire to secure by Letters-Patent is:—

In a device of the character described, the 95 combination of a plurality of screw-threaded bolts having a plurality of longitudinal slots or grooves cut thereon and extending the full length of said threads; fish-plates having a plurality of screw-threaded holes 100

formed therein and adapted to receive the threads of said bolts; and a plurality of inverted Y-shaped pawls pivotally mounted upon collared studs that are secured to said fish-plates in such a manner as to permit one of the arms of said pawls to engage one of the said slots or grooves in said bolts

after the latter have been inserted into the screw-threaded holes in said fish-plates, as and for the purpose set forth. **10**

In testimony whereof, I have signed my name to this specification.

CHARLES PARIDY.
